CLAIM

We claim the ornamental design for a display screen or portion thereof with graphical user interface, as shown and described.

DESCRIPTION

FIG. 1 is a front view of a display screen or portion thereof with graphical user interface according to an embodiment of the invention.

FIG. 2 is a front view of FIG. 1 depicted on a device.

FIG. 3 is a front view of a display screen or portion thereof with graphical user interface according to another embodiment of the invention; and,

FIG. 4 is a front view of FIG. 3 depicted on a device. The broken lines in the drawings illustrate portions of the display screen or portion thereof with graphical user interface that form no part of the claimed design.

1 Claim, 4 Drawing Sheets
